UNITED STATES PATENT OFFICE.

JAMES A. WRIGHT, OF ROCKFORD, ILLINOIS.

DESIGN FOR A HORSESHOE.

SPECIFICATION forming part of Design No. 22,450, dated May 16, 1893.

Application filed April 18, 1893. Serial No. 470,903. Term of patent 14 years.

To all whom it may concern:

Be it known that I, JAMES A. WRIGHT, a subject of the Queen of Great Britain and Empress of India, residing at Rockford, in the county of Winnebago and State of Illinois, have invented and produced a new and original Design for Horseshoes, of which the following is a specification, reference being had to the accompanying drawings, forming a part thereof.

Figure 1 is a front isometric view of a horse shoe showing my design. Fig. 2 is a cross-section of the same, at the dotted line X—X in Fig. 1.

15 The face of this shoe consists of an in-

wardly-inclined peripheral nearly V-shaped flange A, terminating in continuous transverse calks A', a plane depressed inner portion B, and a groove C sunk, at the base of the flange A, into the part B.

Having thus described my invention, what I claim as new, and desire to secure by Letters Patent, is—

The design for a horse shoe as herein shown and described.

JAMES A. WRIGHT.
